UNITED STATES PATENT OFFICE.

JAMES CAMPBELL, OF MONTROSE, CALIFORNIA.

BRICK HAMMER.

Application filed July 3, 1926. Serial No. 120,335.

The present invention relates to a hammer and particularly that type which is commonly used by brick layers.

The prime object of the invention is to provide a blade which is very simple and inexpensive in its construction that may be easily and quickly attached to and detached from the blade of the brick hammer.

10 The blade of the hammer used by brick layers soon becomes dull and it is necessary to take the same to a blacksmith in order to have it sharpened. This consumes considerable time and furthermore the blade of the hammer wears away rather quickly, thus necessitating the purchase of a new hammer.

With my improved blade attachment, it is possible to eliminate these difficulties.

Another very important object of the invention lies in the provision of a detachable 20 blade of this nature, which will prove thoroughly efficient and reliable in use, strong and durable, and otherwise well adapted to the purpose for which it is designed.

With the above and numerous other objects in view as will appear as the description proceeds, the invention resides in certain novel features of construction, and in the combination and arrangement of parts as will be hereinafter more fully described and 30 claimed.

In the drawing:—

Figure 1 is an elevational view of a hammer, embodying the features of my invention.

35 Fig. 2 is a detail perspective view of the blade of the hammer, and

Fig. 3 is a detail perspective view of the auxiliary blade attachment.

Referring to the drawing in detail, it will 40 be seen that the numeral 5 denotes a handle which is received in the socket 6 of the hammer proper. On the socket 6 there is formed in the usual manner the head 7, and the blade 8. In the present instance, the 45 blade is provided with a V-shaped pocket 9 and a pair of V-shaped notches 10 in the centers of the bifurcations formed by the pocket 9.

The auxiliary blade indicated generally 50 by the letter A is of a double wedge forma-

tion, and on one wedge portion, that is, one of the sloping faces of one wedge portion, has a block 11 in the form of a wedge.

One wedge portion of the auxiliary blade A is inserted in the pocket 9 while the wedge block or blocks 11 are receivable in the notches 10. Thus the auxiliary blade is wedged into tight engagement with the blade 8. Obviously, these auxiliary blades may be manufactured at a very small cost, 60 so that when they become worn, they may be thrown away and replaced with a new one, in a much more economical manner than with the ordinary method of resharpening the blade 8.

It is thought that the construction, utility, and advantages of this invention will now be clearly understood by those skilled in this art without a more detailed description thereof. The present embodiment has been 70 disclosed merely by way of example, since in actual practice it attains the features of advantage enumerated as desirable in the statement of the invention and the above description. Numerous changes in the de- 75 tails of construction may be resorted to without departing from the spirit or scope of the invention as hereinafter claimed.

Having thus described my invention, what I claim as new is:—

In combination, a hammer provided with a blade, the end of the blade being provided with a V-shaped pocket, the V-shaped pocket bifurcating the end of the blade, the bifurcations being provided with V-shaped 85 notches and an auxiliary blade having a pair of wedge-shaped terminals and a wedge-shaped block extending laterally from one of the terminals, said one of the terminals being receivable in the pocket and the block 90 being receivable in one of the notches the V-shaped formation of the pocket and the notches and the wedge shaped formation of the terminals and the block being the sole means for retaining the auxiliary blade in 95 the end of the first mentioned blade.

In testimony whereof I affix my signature.

JAMES CAMPBELL.
